UNITED STATES PATENT OFFICE.

DONALD NOBLE, OF LONDON, ENGLAND, ASSIGNOR TO THE WHEELER & WILSON MANUFACTURING COMPANY, OF BRIDGEPORT, CONNECTICUT.

FEEDING MECHANISM FOR SEWING-MACHINES.

SPECIFICATION forming part of Letters Patent No. 651,808, dated June 12, 1900.

Application filed February 21, 1900. Serial No. 6,063. (No model.)

To all whom it may concern:

Be it known that I, DONALD NOBLE, a subject of the Queen of Great Britain, residing at Paul street, Finsbury, London, England, 5 have invented a certain new and useful Improvement in Sewing-Machines, of which the following is a full, clear, and exact description.

My invention has for its object to improve 10 the mechanism employed in sewing-machines for properly presenting the material for the formation of the stitches.

The numerous cloth-actuating mechanisms employed in connection with sewing-machines 15 generally are sufficiently accurate in the control of the feed movements of the plies of the material to satisfy the demands of the trade, except in instances where the slightest variation in the feed movements of one or more of 20 the plies relatively to the feed movements of the remaining ply or plies effects an undesirable production—as, for illustration, when binding one or more plies, wherein the slightest inequality of feed movement in binding 25 and material will cause one or the other to wrinkle, pucker, or draw; again in the seaming of two or more plies having glazed or smooth-finished surfaces, as cambrics, linens, finely-finished silesia, and sateens, and again 30 when it is desired to seam materials sufficiently accurate to carry out the formation 35 of predetermined designs or figures woven or printed into the materials. To this end I have so combined the relative action of cloth-actuating mechanism and needle movement 40 as to compel a synchronous advancement of the plies of the material, thus avoiding the imperfection in production resulting from an imperfect control of the feed movements of the plies relatively one to the other.

The means which I have produced, as herein illustrated and described, to accomplish the results previously recited embodies, I believe, generically, new features of construction, 45 which features of construction perfect the earlier attempts to overcome the difficulties incident to an irregular advancement of the plies of the material. Other advantages attained by the employment of my improved 50 construction are increased speed with improved production and quiet and ease of op-

eration by dispensing with spring-actuated parts and employing suitable connections for the transmission of the power for effecting the necessary operations of the elements comprising the construction, including the employment of an eccentric or crank, in combination with suitable connections for effecting coaction between the eccentric or crank and the oscillating frame carrying the needle-bar 60 and feed-bar, thus greatly reducing the noise, friction, and inaccuracy of operation incident to the employment of springs in distinction to positive actuations.

While it has been selected to illustrate the 65 construction and operation of my invention in connection with the employment of two needles and two complementary loop-takers, such manner of illustrating in no way affects the application of my invention, as it may be 70 employed in connection with one or more needles with equal advantage.

In the accompanying drawings, illustrating 75 my invention, in the several figures of which like parts are similarly designated, Figure 1 is a side elevation, with portions of the arm in section, showing enough of a sewing-machine with my improvements in place to illustrate the arrangement, the needles having about completed the downward movement. Fig. 2 is a front elevation, the position of parts being same as in Fig. 1. Fig. 3 is a front elevation similar to Fig. 2, with the parts beginning the upward movement and finishing the cloth-feeding movement. Fig. 4 is a view 85 similar to Fig. 2, showing the continuation of the upward movements of the needle and feed bar. Fig. 5 is a view similar to Fig. 4, with the parts beginning the downward movement. Fig. 6 is a perspective view of the oscillatory 90 frame and its needle and feed bar. Fig. 7 is a horizontal section substantially in line 77 of Fig. 6.

The bed-plate A, a portion of which is shown in section in Fig. 1, the throat-plate a, the rotating loop-takers E E, the needle-bar H, with its needle-holder h, the needle-bar collar h⁴, the presser-bar F, with its lifter-collar f, spring f³, adjusting-screw R, and presser-lifter f⁴, the cloth-presser G, secured to the 95 presser-bar F, the needle-bar-actuating link N, pivotally attached to the needle-bar by a 100

suitable stud formed on the collar h^4 , its opposite end pivotally secured to the face of the take-up cam C, the take-up cam C, and take-up lever D, the rotating shaft S, mounted in 5 the overhanging arm, and the overhanging arm B are parts common to the construction of the well-known Wheeler & Wilson vertical-hook sewing-machine and enter into the present construction to illustrate one form of application of my invention.

Referring more particularly to Figs. 1 and 6, L is an oscillating frame fulcrumed to the head of the overhanging arm by the pivot-bolt l , said frame carrying a feed-bar K and 15 a needle-bar H, the latter provided at its lower end with a needle-holder h , which in turn is provided with needles secured in the usual manner. P is an eccentric encircling the rotating shaft S and secured to the face of the 20 take-up cam C by the screw p . Coöoperating with this eccentric is an eccentric-strap p^2 , having a downwardly-extending portion p^3 , the inner side of which is provided with a groove p^4 , said extension being provided at its 25 upper end with a slot p^5 , for a purpose later to be explained. Adjustably secured in the downwardly-extending portion of the overhanging arm is a feed-adjusting disk b, provided with a groove b^2 , which latter receives 30 a slide-block b^3 , said block being formed with a stud which receives a screw b^4 to retain in their operative positions a sliding bar b^5 and a connecting-link b^6 , the latter at its opposite end pivotally attached to the oscillating 35 frame L by a pin k^9 . The upper end of the slide-bar b^5 is provided with a roller b^7 , which enters a cam-slot b^{10} in a stationary plate W, the latter secured to the overhanging frame by the screws $w w$. Secured to the presser-bar F is a collar f^2 , formed with a lug f^3 , and 40 pivotally attached to said lug is a rock-lever f^6 , the opposite end of which is pivotally secured to a connection f^7 , which in turn is pivotally attached to the downwardly-extending 45 portion p^3 of the eccentric-strap p^2 .

Referring to Figs. 6 and 7, to the feed-bar K is secured a slide-block k^3 by means of the screws k^4 k^4 , said block carrying a roller k^5 , held in position by a screw k^6 . The rock-lever f^6 is provided with a slot f^{10} for the reception of the roller k^5 , and said rock-lever is actuated from the eccentric P by means of the connection f^7 , downwardly-extending portion p^3 , and eccentric-strap p^2 . When the 55 said rock-lever is so actuated, the roller k^5 acts as a fulcrum for the said rock-lever to lift the presser-bar F and cloth-presser g vertically to permit of the advancement of the material for the succeeding stitch, such movement of the presser-bar occurring when the 60 downwardly-extending portion p^3 is moved downward by the action of the eccentric P, a movement of the downwardly-extending portion p^3 in an opposite direction acting to permit the return of the presser-bar F to its normal position, as illustrated in Figs. 4 and 5, followed by the employment of the pivotal

connection f^5 to move the feed-bar vertically during the continued upward movement of the downwardly-extending portion p^3 . Referring to Fig. 7, the feed-bar K is mounted in a groove k^{10} on the oscillating frame and secured in such operative position by a plate k^7 . To the lower end of the feed-bar is secured an extension k , which at a predetermined time in the formation of the stitch is actuated to advance the material for the succeeding stitch.

Explanatory of the operation of the combined mechanism, Figs. 2, 3, 4, and 5 represent, respectively, the different positions of the elements of construction during four substantially equally divided periods of the rotation of the main shaft S or the time necessary for the formation of a single stitch, 85 which relative positions of parts are more readily understood by observing the substantially-quarterly advancement of the needle-bar link N. Referring to Fig. 2, the needle-bar H is positioned in its downward movement to nearly its limit of stroke. The presser-bar extension G, through the action of the eccentric P and the connections previously recited, is illustrated as lifted above the material. The feed-bar extension k is illustrated 90 as pressing upon the upper surface of the material, the oscillating frame L in its forward position ready to be oscillated to effect a feed movement of the material, the eccentric P in such position that its subsequent substantially-quarterly revolution will force the roller b^7 , carried by the slide-bar b^5 , to the end of the cam-slot b^{10} , as illustrated in Fig. 3, causing the slide-bar b^5 to force the slide-block b^3 downward in the groove b^2 of the feed-adjusting disk b, compelling the link b^6 to oscillate the frame L for effecting a feed movement of the material, causing a relative positioning of parts, as illustrated in Fig. 3. The succeeding step in the substantially-quarterly revolution of the eccentric P causes the downwardly-extending portion p^3 of the eccentric P, through the connection f^7 , to rock the rock-lever f^6 , so as to lift the feed-bar extension k , above the material, at the same 115 time causing the presser-bar extension G to be forced down upon the material and the needle to be raised to nearly the limit of its upward stroke, leaving the parts in the position illustrated in Fig. 4. The position of the parts at the finish of the substantially-quarterly revolution next subsequent is illustrated by Fig. 5, wherein the presser-bar and its extension G and the feed-bar and its extension k retain the same positions, as illustrated in Fig. 4, the oscillating frame having been returned to its position (illustrated in Fig. 2) through the action of the vibratory mechanism, consisting of the eccentric P as prime mover, the eccentric-strap, with its downwardly-extending portion p^3 , the cam-slot b^{10} , with its coating roller b^7 , the slide-bar b^5 , slide-block b^3 , and connecting-link b^6 . The fourth step in the coaction of the parts

5 returns the feed-bar extension K into operative relation with the material to subsequently effect a feed movement, the cloth-presser G raised to permit of the unobstructed advancement of the material, and the vibrating mechanism returned to a position to next effect an oscillation of the frame L to effect a feed movement, all as first recited in connection with the description of Fig. 2.

10 Referring to the mechanism for adjusting the length of feed movement, to the smaller diameter of the feed-adjusting disk b is secured a feed-adjusting lever T, frictionally held in its adjusted position by a spring-washer t. If the feed-adjusting lever T be moved into a position to cause the groove b² in the feed-adjusting disk b to occupy the position illustrated in dotted lines, Fig. 4, the oscillating frame L will be timed to operatively contact the feed-bar extension K and material, when the oscillating frame is moved forward or toward the operator instead of away from the operator, which is the direction previously herein described, making it 25 convenient for the operator to adjust the lever T to effect feed movements in opposite directions.

It will be observed that the cam-slot b¹⁰ in the stationary plate W is more or less inclined 30 from a truly horizontal plane, so that the roller b' has a rising-and-falling motion therein in the cycle of movements just described. From this construction and the arrangement of said cam-slot near the eccentric or prime 35 mover it follows that a quick shifting of the slide-bar and its connected parts is effected.

From the foregoing it will be understood that the function of the feed-bar is to give to the material its feed movements and that the 40 needle through its actuation acts as the regulating power for the synchronous feeding of the several plies. It is true that if no lost motion is to be considered the needle acts in unison with the feed-bar to advance the material; but in actual practice the needle-bar, owing to its range of movement necessary in the formation of the stitches, subjects it and its bearings to excessive wear as compared with the wear on the feed-bar and its bearings, and after a comparatively-short period of practical operation the feed-bar will become the prime member in advancing the material, which mode of operation is favorable to a continued practical operation of my 45 mechanism, thus giving a superiority of construction to the above-mentioned mechanism over similarly-classed constructions, wherein the vibration of the needle-bar is employed to effect a vibration of the feed-bar, and in such instance the lost motion incident to wear compels the needle to continuously act as the prime member for advancing the material, and when such material consists of numerous plies or of extremely-heavy material it can 50 be readily understood that the employment of the needle as the prime member for effect-

ing the feed movements of the material is not a desirable mode of operation.

It is not intended that the mechanism herein illustrated and described shall be considered as a strictly non-needle-feeding mechanism, as the needle might be employed for the advancing of the material without departing from the spirit of my invention; but it is desirable and advantageous that the mechanism be so arranged as to cause the feed-bar to act as the prime member for giving to the material its feed movements.

What I claim is—

1. In a sewing-machine, a stitch-forming mechanism, a cloth-actuating mechanism pivoted to the head of the overhanging arm, said cloth-actuating mechanism including an oscillating frame, a feed-bar mounted in independent bearings in said frame, and constructed and arranged to coöperate with the needle to effect a synchronous feeding of two or more plies of material for the formation of a seam, in combination with an eccentric 85 operatively connected with the oscillating frame, for giving to said feed-bar and needle-carrying bar oscillating movements in the direction of the feed of the material, substantially as described.

2. In a sewing-machine, a stitch-forming mechanism including an oscillating needle-carrying bar, a cloth-actuating mechanism including an oscillating feed-bar, an oscillating frame pivoted at its upper end in the head of the overhanging arm and having independent 100 bearings for said needle-carrying bar and feed-bar, said frame capable of oscillation in the direction of the line of feed of the material, in combination with an eccentric and suitable connections for connecting the oscillating frame with the eccentric, substantially as described.

3. In a sewing-machine, a stitch-forming mechanism including an oscillating needle-carrying bar, a cloth-actuating mechanism including an oscillating feed-bar, an oscillating frame having independent bearings for said needle-carrying bar and feed-bar, said frame capable of oscillation in the direction of the line of feed of the material, in combination with an eccentric and suitable connections for connecting the oscillating frame with the eccentric, substantially as described.

4. In a sewing-machine, the combination with an oscillating frame, a reciprocating needle-bar and a reciprocating feed-bar mounted in independent bearings in said frame, and a presser-foot, of a prime mover, such as a rotary eccentric, a rock-lever connected with said feed-bar, and means interposed between said prime mover and rock-lever to periodically lift and depress said feed-bar, substantially as described.

5. In a sewing-machine, an oscillating frame, a reciprocating needle-bar and a reciprocating feed-bar mounted in independent bearings in said frame, and a presser-bar,

in combination with a prime mover, such as a rotary eccentric, a rock-lever attached at one end to said presser-bar, and fulcrumed to the feed-bar, and connections between the other end of the rock-lever and said prime mover, substantially as described.

5 6. In a sewing-machine, a stitch-forming mechanism including a reciprocating needle-carrying bar, a cloth-actuating mechanism including a reciprocating feed-bar, a presser foot and bar, a rotary eccentric, an eccentric-strap having a depending portion, and a rock-lever pivoted at one end, fulcrumed to the feed-bar and connected with said depending portion at its other end, whereby the feed-bar and presser-bar are alternately lifted and depressed, substantially as described.

10 7. In a sewing-machine, the combination of stitch-forming mechanism including a reciprocating needle-carrying bar, a cloth-actuating mechanism including a reciprocating feed-bar, an oscillating frame having bearings for said bars, a prime mover, such as a rotary eccentric, connections between said 15 prime mover and frame including a slide-bar, and a stationary portion having a cam-slot

engaged by said slide-bar to effect a quick shifting of the slide-bar and oscillation of the frame, substantially as described.

8. In a sewing-machine, a stitch-forming mechanism including a reciprocating needle-carrying bar, a cloth-actuating mechanism including a reciprocating feed-bar, an oscillating frame having bearings for said bars, a presser foot and bar independently mounted, a rotary eccentric, a depending strap, a rock-lever connected at one end to the presser-bar, fulcrumed to the feed-bar and operatively connected with the depending strap alternately to raise and lower the feed-bar and presser-bar, and a connection between said depending strap and the oscillating frame to effect the necessary feed, substantially as described.

30 35 In testimony whereof I have hereunto set 45 my hand this 15th day of February, A. D. 1900.

DONALD NOBLE.
